(57) **CLAIM**

The ornamental design for a beverage cup lid, as shown and described.

DESCRIPTION

FIG. 1 is a perspective top view of a new design for a beverage cup lid;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

Broken lines are used to illustrate features of the beverage cup lid that form no part of the claimed design.

1 Claim, 6 Drawing Sheets
